UNITED STATES PATENT OFFICE.

S. BOURNE, JR., AND J. G. CUNNINGHAM, OF NEW YORK, N. Y.

LOCK FOR TRAVELING BAGS.

Specification of Letters Patent No. 28,057, dated May 1, 1860.

To all whom it may concern:

Be it known that we, SHEARJASHUB BOURNE, Jr., and J. G. CUNNINGHAM, both of the city, county, and State of New York, 5 have invented a new and Improved Fastening for Frames of Traveling-Bags, &c.; and we do hereby declare that the following is a full, clear, and exact description of the same, reference being had to the accompanying drawings, forming a part of this specification, in which—

Figure 1, represents an inside view of our invention. Fig. 2, is a horizontal section of the same, taken in the plane indicated by 15 the line x, x , Fig. 1, and Fig. 3, is a modification of the same.

Similar letters of reference indicate corresponding parts in the three figures.

The frames of traveling bags, valises etc. 20 must necessarily be made light and thin and if they are fastened in the middle only and when the bag is well filled, the ends of the frame are forced apart and the contents of the bag are exposed. It has therefore been 25 proposed to fasten the frames at two points a certain distance from each other and this fastening holds the frames together even when the bag is well filled. But another difficulty arises. If the bag is well filled so 30 that it requires some force to bring the two parts of the frame together, it is impossible to hold the frame together with one hand and to turn the key with the other so that the bolt catches in both eyes at the same 35 time. If the frame be compressed in the neighborhood of one eye, it will spread at the other end and it is not without great trouble that a bag with such a double fastening can be locked.

40 To remove all those difficulties and to render a double fastening of such frames practicable we have arranged our fastening in such a manner that it takes two consecutive and distinct motions of the key to throw 45 the two bolts into the eyes so that the frame can be compressed in the neighborhood of one eye and by giving to the key one turn or a portion of a turn, the bolt is brought to catch into said eye and the other end of 50 the frame can now be compressed and locked in the same manner.

To enable those skilled in the art to make

and use our invention we will proceed to describe it.

Our fastening is arranged in a casing A, 55 which is secured to the frame in the usual manner, the casing A, being on one part and the plate B, with the eyes a, a' , on the other part of the frame. The bolt C, when constructed as represented in Figs. 1 and 2, consists of one long strip of sheet metal, which slides in the casing A, by means of slots b , and guide pins c , and which is thrown backward and forward by means of a key D, that catches into the notches d , in the usual manner. A notched spring catch E, retains the bolt in the desired positions. The bolt catches into the eyes a, a' , by means of noses e, e' , the nose e , being close to the eye a , so that by turning the key once this nose 65 catches into the eye a . The nose e' , on the other hand is so far removed from the eye a' , that by the first motion of the key it is drawn up close to said eye without however catching into it and that it takes a second turn of the key to bring the nose e' , into the eye a' .

Instead of arranging the fastening as here described, it can however with equal advantage be constructed as represented in Fig. 3. 80 Instead of using one bolt, two bolts C^* , and C'^* , are employed each with one notch d^* and d'^* , for the key to catch in and each furnished with a separate notched spring catch E^* , and E'^* . By turning the key half 85 way the bolt C^* , is moved and its nose e^* , is brought to catch into the eye a^* , and by completing the revolution of the key the other bolt C'^* , is thrown forward and its nose e'^* , catches into the eye a'^* .

90 In both cases it takes two distinct consecutive motions of the key to lock both ends of the frame so that when the bag or valise is well filled and one end of the frame spreads when the other is compressed, one 95 end can be locked by compressing it first and by giving to the key one turn or a portion of a turn and the other part can now be locked without difficulty by a second motion of the key.

100 It will be noticed that our fastening can be got up just as easy and cheap as ordinary fastenings with two catches and while it does not increase the price of the bag or

valise it renders the same much more valuable and easier to handle.

What we claim as new and desire to secure by Letters Patent, is,

5 The combination with the plate A, casing B, and eyes (a, a') of a long nose (e) and a short nose (e') when the said noses are attached to the extremities of a longitudinal bolt C, and so arranged to operate that the

long nose first enters one of the eyes (a) 10 and then the short nose enters the other eye as and for the purposes herein shown and described.

SHEARJASHUB BOURNE, JR.
JOHN G. CUNNINGHAM.
